his Atty's.

UNITED STATES PATENT OFFICE.

JAMES F. SMITH, OF ST. LOUIS, MISSOURI, ASSIGNOR OF ONE-THIRD TO ANTHONY F. ITTNER AND ONE-THIRD TO ARTHUR H. BRADLEY, BOTH OF ST. LOUIS, MISSOURI.

SOUND BOX FOR TALKING MACHINES.

1,412,294.

Specification of Letters Patent. Patented Apr. 11, 1922.

Application filed April 23, 1919. Serial No. 293,212.

To all whom it may concern:

Be it known that I, JAMES F. SMITH, a citizen of the United States, and a resident of the city of St. Louis and State of Missouri, have invented a new and useful Improvement in Sound Boxes for Talking Machines, of which the following is a specification.

This invention relates to sound-boxes for talking machines and particularly to the connection between the stylus lever and the sound-box; and the invention is an improvement in the construction shown in my Patent No. 1,302,479, dated April 29, 1919.

One of the principal objects of the present invention is to provide a pivotal mounting for the stylus lever which will permit movement of the stylus lever in two vertical directions at right angles to each other, thereby enabling the stylus lever to continuously engage the undulating surface of the record grooves and thus eliminating objectionable sounds and improving the tone quality and volume of sound produced. Another object of the pivotal mounting of the stylus lever is to obtain free movement of the stylus lever thereby permitting the stylus to closely follow the irregularities of records having either perpendicularly or laterally undulating record grooves.

The invention consists principally in means for pivotally connecting the stylus lever to the sound-box casing whereby free motion of the stylus lever is permitted in two vertical directions at right angles to each other; and it also consists in the combinations and arrangements of parts herein-after described and claimed.

In the accompanying drawing, wherein like symbols refer to like parts wherever they occur,

Fig. 1 is a face view of a sound-box, showing a stylus lever mounting embodying my invention;

Fig. 2 is a side view of the same;

Fig. 3 is a vertical cross-section through the supporting bracket and spring support for the stylus lever, the section being taken on the line 3-3 in Fig. 2;

Fig. 4 is a horizontal section through the supporting bracket and stylus lever on the line 4-4 in Fig. 2;

Fig. 5 is a bottom plan view of the sound-box and stylus lever support;

Fig. 6 is an enlarged vertical section taken

through the pivots which support the stylus lever; and

Fig. 7 is an enlarged vertical section taken through the pivots which support the collar in which the stylus lever is pivotally supported, the section being taken at right angles to the section shown in Fig. 6.

Referring to the drawing, the invention is shown illustrated in connection with the sound-box and stylus lever support shown in my pending application Serial No. 187,922, filed August 24, 1917. The sound-box comprises a supporting casing 10 provided with a diaphragm 11 and having a hollow stem portion 12 which forms means for attaching the sound-box to the free end of the tone arm (not shown) and forms communication therebetween.

The stylus lever 13 is tapered upwardly and terminates in a horizontal coil 14, the inner end of which is soldered or otherwise secured to the middle portion of the diaphragm and constitutes a flexible connection between the diaphragm and the upper end of the stylus lever 13. A stylus 15 is inserted in a socket formed in the lower end of the stylus lever and is held therein by means of a knurled screw 17. The form of stylus depends on whether the stylus is to be used with tablets having perpendicularly undulating record-grooves or with tablets having laterally undulating record-grooves.

The free end of the stylus lever 13 is pivotally supported at the outer end of a horizontally disposed flat plate or spring 18 in a manner hereinafter more fully described. The spring 18 is supported from the sound-box by means of a supporting bracket which comprises a vertical flange 19, which is adjustably secured to the front face of the sound-box and a horizontal base flange 20, which extends rearwardly beneath the sound-box and has a forwardly extending arm 21 located beneath and parallel with the base flange 20 but spaced therefrom far enough to accommodate a clamp 22. The rear end portion of the spring 18 is adjustably secured by means of screws 23 to the rear end of the arm 21 of the supporting member, and is insulated therefrom by sound insulating blocks 24. One of said blocks is arranged between the arm 21 and the supporting member, and the other block is disposed below the spring 18. The spring 18 is adjustable towards and away from the lever

arm 13 by the screws 23, which pass through slots 25 in the spring 18 and screw into the rear end portion of the supporting member. These screws also pass through the insulating blocks 24 to hold them in position.

The forwardly extending arm 21 of the supporting member carries the clamp 22 which embraces the spring 18. This clamp 22 is slideable on the arm 21 of the supporting member and spring 18 for adjusting the amplitude of the vibrations of the stylus lever 13. The clamp 22 is insulated from the spring 18 by suitable sound insulating blocks 25.

15 Located at the forward end of the spring 18 is a clip 26 of inverted channel-shape, which is provided with a lateral base flange 27 riveted or otherwise secured to the forward end portion of the spring 18. The horizontal web portion of the clip 26 is provided with a large opening 28 through which the stylus lever passes. The lower end of the stylus lever extends through a collar or yoke 29 and is mounted therein for oscillation upon a horizontal axis in a plane parallel with the front face of the sound-box by means of oppositely disposed pivot studs 30 which are threaded into the opposite sides of the collar 29. These pivot studs 30 are 20 adjustable towards and away from each other and are held in the desired adjusted position by means of jam-nuts 31 located at the outer ends of the studs.

25 The stylus lever is provided with a rod or spindle 32 which extends through the stylus lever 13 and projects therefrom a suitable distance on opposite sides of the same. The spindle 32 fits tightly in the stylus lever so as to turn therewith and its opposite ends are journaled in the sound insulating plugs 33, which are mounted in a bore in the adjacent ends of each pivot stud 30. The opposite ends of the spindle terminate short of the end of the bore in each pivot stud thus permitting endwise movement of the spindle. The stylus lever is normally held in a position midway between the pivot studs 30 by means of a pair of coiled springs 34 which are sleeved on each 40 end of the spindle and are insulated from the stylus lever by means of sound insulating washers 35.

50 The collar 29 is in turn mounted on the clip 26 for oscillation upon a horizontal axis by means of oppositely disposed horizontal pivot studs 36. These studs are threaded into the side flanges of the clip 26 and extend through the collar 29, and pivotally support the same. The pivot studs 36 which 55 support the collar 29 are adjustable towards and away from the collar and are held in adjusted position by means of jam-nuts 37. The collar 29 is permitted to move longitudinally of the pivot studs 36 upon which it 60 is supported and is normally held in posi-

tion midway between the side flange of the clip 26 by means of coiled springs 38. These coil springs are sleeved on the pivot studs 36 and are located between the outer wall of the collar and the inner face of the side 70 flange of the clip 26. The pivot studs 30 which support the stylus lever are arranged at right angles to the pivot studs 36 which support the collar, thus permitting the stylus lever 13 to oscillate upon horizontal axes at 75 right angles to each other and also permitting bodily movement of the stylus lever in two horizontal directions at right angles to each other. This movement of the stylus lever in two directions is permitted by reason 80 of the flexible connection between the upper end of the stylus lever and the diaphragm and results in free movability of the lower end of the lever arm 13, which permits the stylus point to closely follow and continuously engage the record surfaces of the tablets having either perpendicularly or laterally undulating record-grooves.

85 The foregoing arrangement is considered only as an example and as being the one best 90 adapted for the style of sound-box and spring support shown, but I do not wish to be limited thereto, as the invention is applicable to other styles of sound-box having rigid or spring stylus lever supports without 95 departing from the invention.

What I claim is:

1. In combination with a sound-box for talking machines comprising a diaphragm and a supporting casing, a stylus holder 100 comprising a lever arm connected at one end to said diaphragm and supporting a stylus at its other end, and a collar supported on said supporting casing and adapted to receive said lever arm, said collar being mounted on oppositely disposed horizontal pivots 105 on said supporting casing, and said lever arm being mounted on oppositely disposed horizontal pivots in said collar, said lever arm and said collar being arranged for bodily movement longitudinally of their respective pivots which are arranged at right angles to each other, whereby the stylus lever is permitted to move bodily in two horizontal directions at right angles to each other 110 and is permitted to oscillate upon horizontal axes at right angles to each other.

115 2. In combination with a sound-box for talking machines comprising a diaphragm and a supporting casing, a stylus holder 120 comprising a lever arm connected at one end to said diaphragm and supporting a stylus at its other end, a collar mounted on oppositely disposed horizontal pivots on said supporting casing and arranged for bodily movement longitudinally of said pivots, said lever arm being mounted on oppositely disposed horizontal pivots in said collar and arranged for bodily movement longitudinally of said pivots, the oppositely disposed 125

pivots which support said stylus lever being arranged at right angles to the oppositely disposed pivots which support said collar whereby said stylus lever is permitted to oscillate upon horizontal axes at right angles to each other, and yieldable means supported on the pivots for said collar and the pivots for said collar and the pivots for said stylus and arranged between said collar and 5 said supporting casing and between said collar and said lever arm for normally maintaining said collar and said lever arm midway between their supporting pivots.

3. In combination with a sound-box for 10 talking machines comprising a diaphragm and a supporting casing, a stylus holder

comprising a lever arm connected at one end to the diaphragm and supporting a stylus at its other end, a collar slidably mounted on oppositely disposed pivots on said supporting casing, the stylus end of said lever arm having oppositely extending spindle portions slidably mounted in pivots arranged at right angles to the pivots which support said collar, and yieldable means mounted 20 on the pivots for said collar and the pivots for said stylus for normally maintaining said collar and said lever arm midway between their supporting pivots.

Signed at St. Louis, Missouri, this 26th 25 day of April, 1919.

JAMES F. SMITH.
